[57] CLAIM

The ornamental design for a sport shoe lacing, as shown and described.

DESCRIPTION

FIG. 1 is an environmental perspective view of a first embodiment of a sport shoe lacing showing my new design; FIG. 2 is a front elevational view thereof; FIG. 3 is a rear elevational view thereof; FIG. 4 is a top plan view thereof; FIG. 5 is a right side elevational view with the left side view being a mirror image thereof; FIG. 6 is an environmental perspective view of a second embodiment of my new design; FIG. 7 is a front elevational view thereof; FIG. 8 is a rear elevational view thereof; FIG. 9 is a top plan view thereof; and, FIG. 10 is a right side elevational view with the left side view being a mirror image thereof.

The broken line showing of the various shoe parts in the figures is for illustrative purposes only and forms no part of the claimed design.
